UNITED STATES PATENT OFFICE.

ALBION DYKE, OF NASHUA, NEW HAMPSHIRE.

DESIGN FOR A BUCKLE.

SPECIFICATION forming part of Design No. 12,305, dated June 14, 1881.

Application filed February 11, 1881. Term of patent 14 years.

To all whom it may concern:

Be it known that I, ALBION DYKE, a citizen of the United States, residing at Nashua, in the county of Hillsborough and State of New Hampshire, have invented and produced a new and original Design for the Ornamentation of Buckles, of which the following is a specification.

Referring to the drawing forming part of this application, the figure is a plan view illustrating my invention.

The leading feature of my design consists in a buckle-frame having the side bars and one end bar widened and surfaced upon the upper side, having delineated thereon the ornamental pattern shown and described.

A in the drawing indicates the side bars of an ordinary four-barred buckle, and B indicates one of the end bars. The side bars, A, are flattened and extended upon their upper or outward side, and are surfaced in such a manner as gives the space needed for the application of a suitable ornamental pattern, which I apply directly to the upper surface in any desired manner. The end bar, B, which unites the two side bars, may be made somewhat broader, and may also be slightly bowed or arched in order to give the most graceful proportions and outlines. Upon the flat upper

surface of the buckle-frame I apply an ornamental design of a character suited to the space which it must occupy, as well as to the arrangement of that space. This design or pattern may be applied to the broadened end bar, B, and may be confined within a border-line, a, as shown in the figure. The pattern applied to the buckle-frame, as well as the border-line, when the latter is used, may be either engraved, stamped, cut, inlaid, or otherwise applied to the said frame. I may also add that the upper surface of the buckle need not be perfectly flat, but may be more or less rounded or swelled upward without departing from the characteristic features of my design.

I claim—

A buckle-frame having its upper or outward surface broadened, as described, and having the ornamental pattern described and shown, and having a border-line surrounding said pattern.

In testimony whereof I have signed my name to this specification in the presence of two subscribing witnesses.

ALBION DYKE.
